LIQUID FUEL BURNER NOZZLE

Filed Jan. 5, 1928

Inventor
Albert V. Rigby.

By Clarence O'Brien
Attorney

UNITED STATES PATENT OFFICE

ALBERT V. RIGBY, OF SHARON, PENNSYLVANIA, ASSIGNOR OF ONE-HALF TO CARL J. MEHLER, OF SHARON, PENNSYLVANIA

LIQUID-FUEL-BURNER NOZZLE

Application filed January 5, 1928. Serial No. 244,757.

The present invention relates generally to liquid fuel burners and more particularly to the nozzle thereof and has for its prime object to provide an automatic and hand cleaning mechanism.

Another very important object of the invention resides in the provision of a nozzle of this nature which is simple in its construction, inexpensive to manufacture, strong and durable, not likely to become out of order, easy to adjust, thoroughly efficient in use and operation, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a longitudinal section through a burner embodying the features of my invention,

Figure 2 is a detail transverse section through the nozzle taken substantially on the line 2—2 Figure 1, and

Figure 3 is a detail side elevation of one end of the nozzle.

Referring to the drawing in detail it will be seen that the numeral 1 denotes the nozzle body which is of an elongated construction having a longitudinally extending bore throughout its length. This nozzle tapers

from one end toward the other and is provided adjacent its larger end with an exterior annular shoulder 10 and with threaded portions to each side thereof. The smaller end of the nozzle is beveled off and provided with

a plurality of V-shaped notches 11. A nozzle casing is denoted generally by the letter C and may be conventional or of any preferred construction wherein proper air ducts or passages are arranged so as to convey air or steam into oil at counter directions one or more places to atomize or molecularize the oil for combustion. The casing in the present instance includes a body 12 with a partition 13 therein to provide two air ducts 14 and

15. A restricted end 16 is threaded about

the outlet end of the duct 14 and a similar member 17 is threaded about outlet end of the duct 15. A cap 18 is threaded on the casing and partitioned as at 19 so that air or steam from pipes 20 and 21 may be led respectively into ducts 14 and 15. The major portion of the nozzle body 1 extends into the casing and into the passage 14. This nozzle body is threadedly engaged in the casing with the annular shoulder in abutment therewith. 55 A T 2 is threadedly engaged on the larger end of the nozzle body 1. A cap 3 is screwed into the opposite end of the T to prevent the escape of fume and has a stuffing box 4 thereon through which is slidably a rod 5. A 60 fuel pipe 22 is threadedly engaged in the T 2 for delivering liquid fuel thereto. A valve stem 6 is slidable through the bore of the nozzle body 1 having the centralizing spider 7 thereon. A valve 23 is mounted at 70 the end of the stem 6 to close over the smaller end of the nozzle 1. The nut 9 is threaded on the other end of the stem 6 and a compression spring 8 is disposed about the stem impinging against the larger end of the nozzle body 1 and the nut 9. Obviously the nut 9 may be adjusted for changing the tension of the spring 8.

The flow of the fuel from the pipe 22 extends through the T 2 and the bore of the 80 nozzle 1 and the pressure will unseat the valve 23 if sufficient to overcome the tension of the spring 8. An idling amount of fuel may also escape through the notches 11.

The compression spring 8 is utilized to 85 vary the discharge of the fuel through the nozzle and out at the angular outlet afforded by the valve 23 at any desired pressure. The series of V-shaped notches 11 flaring outwardly greatly facilitate the passage of 90 smaller particles. In case the V-shaped notches in the chamber become partially or totally closed, pressure automatically builds up in the nozzle body until it is sufficient to overcome the tension of the spring and open 95 the valve. It is also obvious that the rod 5 may be pushed inwardly to engage the valve stem 6 and unseat the valve 23 if it should be necessary.

It is thought that the construction, opera- 100

tion and advantages of this invention will now be quite apparent to those skilled in this art without a more detailed description thereof. The present embodiment of the invention has been disclosed in detail merely by way of example since in actual practice it attains the features of advantage enumerated as desirable in the statement of the invention and the above description.

10 Having thus described my invention, what I claim as new is:

15 A nozzle of the class described comprising an elongated body having a longitudinally extending bore extending from end to end thereof, one end of the body being provided with a plurality of notches, a valve closable over said end of the body, a stem extending from the valve through the bore, spiders on the stem to centralize the stem in the bore, a 20 spring about the stem, a nut threaded on the stem at the end remote from the valve, said spring impinging against the other end of the body and the nut to urge the valve toward the first mentioned end of the body, a **T** 25 threadedly engaged on said other end of the body, a cap threadedly engaged in the **T**, a stuffing box in the cap, a rod slidable through the stuffing box in alignment with the valve stem.

30 In testimony whereof I affix my signature.
ALBERT V. RIGBY.
